UNITED STATES PATENT OFFICE.

THOMAS JOSEPH CONDON, OF AYER, MASSACHUSETTS.

SWIMMING DEVICE.

1,411,909.

Specification of Letters Patent.

Patented Apr. 4, 1922.

Application filed September 10, 1921. Serial No. 499,689.

To all whom it may concern:

Be it known that I, THOMAS J. CONDON, a citizen of the United States, and a resident of Ayer, in the county of Middlesex and 5 State of Massachusetts, have invented a new and Improved Swimming Device, of which the following is a description.

My invention relates to an attachment adapted to be applied to each foot of a swimmer and arranged to be an aid to the swimmer.

The general object of the invention is to provide a swimming device including wings adapted to fold and to spread with movements of the foot of the swimmer, and having novel means for comfortably and securely holding the device in position.

The nature of the invention and its distinctive features and characteristics will 20 clearly appear as the description proceeds.

Reference is to be had to the accompanying drawings forming a part of this specification, it being understood that the drawings are merely illustrative of one example of 25 the invention.

Figure 1 is a side elevation of a swimming device embodying my invention, showing the same in position for use;

Figure 2 is a side elevation with one of the 30 wings removed, to show the interior construction;

Figure 3 is a front elevation with the wings folded and indicating the spread position of the wings by dotted lines;

35 Figure 4 is a front elevation showing the wings in spread form.

In carrying out my invention in accordance with the illustrated example a pair of wings 10 is provided, the upper edges of 40 which at the rear portions 11 are permanently united by stitching or other means. The wings are separate at their front portions 12 at their upper edges, for the convenient application of the device to the ankle 45 and foot of the user.

Between the pair of wings is an anklet 13 from which a rear extension 14 extends between the upper rear portions 11 of the wing and permanently secured with the se-

curing of the latter. At the front of the anklet 13 is a front extension 14^a and united to the respective sides of the wings by stitching or otherwise. Transverse holes 15 extend through each wing and ankle extension 55 14^a adapted for receiving a lace 16, although other fastening means may be provided in practice, as will be obvious.

At the interior of the ankle I provide stirrups 17, the sides of which are formed 60 of stiff material and advantageously formed with loops 17^a at the ankles so as not to bear on the ankles and afford discomfort. The lower end is in the form of a strap 17^b adapted to lie beneath the foot of the user and 65 an instep strip 18 connects the sides of said stirrup strap 17^b.

To limit the spreading movement of the wings 10 I provide flexible elements 19 connecting the outer portions of the wings with 70 the stirrup 17.

With the described arrangement the swimming device having been attached in position on the ankle and foot of the wearer, the forward and backward movement of the 75 foot in swimming will cause the wings to alternately fold and spread, the spread form of the wings affording a material resistance in the rearward movement of the foot in swimming.

I would state in conclusion that while the illustrated example constitutes a practical embodiment of my invention, I do not limit myself strictly to the exact details herein illustrated, since, manifestly, the same can 85 be considerably varied without departure from the spirit of the invention as defined in the appended claims.

Having thus described my invention, I 90 claim:

1. A swimming device including foldable wings at opposite sides of the device, an anklet joined at the top thereof to the upper portions of the respective side wings, the sides of said anklet forming integral forward extensions held respectively to the forward portions of the respective wings, and separable fastening means to fasten the front portion of a wing with the adjacent anklet 95

extension to the front portion of the opposite wing and to the integral anklet extension associated with said opposite wing.

2. A swimming device including a pair of 5 foldable wings separate at their front portions, an anklet having a rearward extension permanently secured at its upper portion to the upper rear portions of both wings

and having a front extension formed with separate sides secured to the separate front 10 portions of the wings, and means to detachably fasten the said sides of the front extensions and the separate front portions of the wings together.

THOMAS JOSEPH CONDON.
